UNITED STATES PATENT OFFICE.

SEYED KHALIL, OF NEWARK, NEW JERSEY, ASSIGNOR OF ONE-FOURTH TO JULES E. TEPPER, OF NEWARK, NEW JERSEY, AND OF ONE-FOURTH TO FRANCOIS SAM-MARCELLI, OF NEW YORK, N. Y.

DIOPTROGRAPH.

Application filed November 18, 1924. Serial No. 750,538.

To all whom it may concern:

Be it known that I, SEYED KHALIL, a citizen of the United States, and a resident of Newark, in the county of Essex and State of New Jersey, have invented certain new and useful Improvements in Dioptographs, of which the following is a specification.

The invention relates to improvements in dioptographs. The term "dioptograph" is taken from two Greek words "dioptra" and "graph."

The object of this machine is for the purpose of ascertaining the dioptographic angle or angles of any natural or artificial structure or design or impression, so that with the use of a similar instrument the lines of such structure, object or impression may be reproduced on a screen by setting the parts of said instrument at the same angles ascertained by the primary machine. The machine will be used for reproducing finger prints, cipher writing, solving algebraic problems, solving geometrical problems, drawing charts and regular or irregular outlines generally. For illustration, if a finger print is taken on a piece of paper and reflected on a screen by the reflecting mechanism of the dioptograph, the refractory mechanisms of the dioptograph may be manipulated to register the dimensions of the lines of the finger print, however irregular such lines may be. The registration of the lines of the finger print is secured by the proper manipulation of the refractory mechanisms of the machine, with the use of certain standard slides employed therein, the manipulation of the refractory mechanisms and slides being indexed on the instrument so that anyone, even at a great distance, having a duplicate dioptograph may reproduce an exact facsimile of the finger print by a corresponding manipulation of his refractory mechanisms and slides, the index registrations or angles of the primary

instrument having been communicated to him by cable or otherwise. I employ the expression "dioptographic angle" as indicating the angles at which the refractory mechanisms may be set, in connection with the adjustment of the standard slides, and it is this dioptographic angle which the holder of the primary machine will communicate to the holder of a similar machine for the reproduction on screen of the image

first reflected on the screen of the primary machine by the reflector mechanism thereof.

The dioptograph comprises in its preferred construction a reflector mechanism for impressing on a screen the outlines of the natural or artificial object to be reproduced and a refractory mechanism or refractory mechanisms, plus certain standard slides to be used therewith, for ascertaining the dioptographic angle of said object as reflected onto the screen. The machine will be accompanied by a number of different types of interchangeable slides for use in the refractory mechanisms, these slides having certain lines thereon which in the refractory mechanisms will, by a proper manipulation, be caused to coincide exactly with the outlines of the object subject-matter, so that with the use of similar slides and similar refractory mechanisms set to the index adjustments of the primary refractory mechanisms, the exact outline of the subject-matter impression may be reproduced.

The machines will be of two classes, one comprising general machines, all of the same detailed construction and accompanied by the same types of slides having outlines thereon to be arbitrarily adopted as a standard. General machines may be used for all purposes, but preferably not for cryptography. The machines for cryptography I regard as special machines to be built of different designs from the general machines and also of different designs for different correspondents, it being desirable that only the machines used between the same correspondents of the same cryptography should be built exactly alike. The type of slides for the general machines will be limited to a certain number of standard design, while the type of slides for special machines for cryptography, will be adopted secretly between the operators of the same duplicated special machines.

The reflector mechanism may vary in type, the object of the reflector mechanism being to accurately transmit to a screen the particular design in hand, whether it be that of a finger print, a drawing or other subject-matter. The refractory mechanisms will each be alike and each comprise a barrel portion having at its front end a suitable lens capable of being tilted or adjusted on its own axis, means for tilting said bar-

rel portion on its horizontal axis, means for adjusting said barrel portion carrying the lens laterally on a vertical axis, and slides to be mounted in said barrel portion and 5 adjusted toward and from the lens, plus means for accurately indexing the angle of the lens, the angle of the vertical adjustment of said barrel portion, the angle of the lateral adjustment of said barrel portion 10 and the position of the slide within said barrel portion. The reading of these indexes will represent what I term to be the dioptragraphic angle of the subject-matter, and a record of the index readings 15 sent to anyone having a similar machine will enable such person to so set the refractory mechanisms and slides of his machine as to reproduce the exact outlines and dimensions of the object subject-matter without 20 the use of the reflector mechanism.

The invention will be fully understood from the detailed description hereinafter presented, reference being had to the accompanying drawings, in which:

25 Fig. 1 is a top plan view, partly broken away, of a dioptragraph constructed in accordance with and embodying my invention;

Fig. 2 is a central longitudinal transverse 30 section through one of the refractor mechanisms forming a portion of the dioptragraph, the section being on the dotted line 2-2 of Fig. 3;

Fig. 3 is a side elevation of the same;

35 Fig. 4 is a vertical transverse section through the same taken on the dotted line 4-4 of Fig. 2;

Fig. 5 is a rear or back end view of the same;

40 Fig. 6 is a vertical transverse section through the same taken on the dotted line 6-6 of Fig. 3;

Fig. 7 is a vertical longitudinal section 45 through the same taken on the dotted line 7-7 of Fig. 2;

Fig. 8 is a central vertical longitudinal section through a reflector mechanism and screen which constitute portions of the dioptragraph, the section being on the dotted 50 line 8-8 of Fig. 1;

Fig. 9 is a vertical transverse section through the reflector mechanism taken on the dotted line 9-9 of Fig. 8;

Fig. 10 is a front view of the screen 55 shown in Fig. 8, said screen bearing an image reflected thereon by the reflector mechanism;

Fig. 11 is a detail section taken on the dotted line 11-11 of Fig. 8 and illustrates 60 a latch for securing the back door of the reflector mechanism in closed position;

Figs. 12 to 19 inclusive, illustrate various 65 slides which may be considered standard, to be employed in the primary refractor mechanism or refractor mechanisms for de-

termining the dioptragraphic angle or angles of the image reflected on the screen by the reflector mechanism and which image when said angle is or angles are ascertained may be reproduced on a screen by a similar 70 slide and refractor mechanism or refractor mechanisms at a great distance away, by setting the same at said angle or angles;

Fig. 20 is a face view of the object or 75 subject-matter having or bearing the design or outline shown, to be reflected upon the screen by the reflector mechanism and which is to be then subjected to admeasurement by the refractor mechanisms with the use of two of the slides of the type shown 80 in Fig. 12, one of said slides being placed in each refractor mechanism;

Figs. 21 to 24 inclusive represent the different stages of outlines progressively obtained with the use of the two refractor 85 mechanisms and two of the slides shown in Fig. 12 in the process of transforming the images refracted from the said slides and focused onto the aforesaid screen to an exact coincidence with the object subject- 90 matter already reflected onto the screen, Fig. 21 showing the first or an early stage of the reproduction and obtainable by tilting the lenses of the refractor mechanisms, Fig. 22 illustrating a further stage thereof 95 obtained by adjusting the slides nearer to the lenses, for enlarging the refracted image or outlines, Fig. 23 showing a further stage thereof obtained by turning the refractor mechanisms horizontally to further separate 100 their forward ends from each other, thus displacing the elements of the reflected image laterally, and Fig. 24 representing the final stage in the reproduction obtained by vertical adjustment of the refractor mechanisms 105 to cause the refracted image to exactly coincide with and be impressed upon the reflected image on the screen;

Fig. 25 shows an image, for instance a conventional finger print, to be reflected 110 onto the screen by the reflector mechanism and admeasured by the refractor mechanisms, and

Figs. 26 and 27 represent different stages 115 of outlines obtained with the use of four refractor mechanisms each containing a slide of the type shown in Figs. 12, 14, 17 and 19, respectively, in the process of reproducing the image shown in Fig. 25, the admeasurements or angles of the reproduction 120 of the image being readable on the indexes with which the refractor mechanisms are equipped.

In the drawings 30 denotes the reflector 125 mechanism as a whole and 31 the screen on which the images are to be reflected, while 32 and 33 respectively indicate the refractor mechanisms, it being understood that one or more refractor mechanisms will be made use of, as occasion may require. At present 130

I have shown the reflector, screen and refractors as mounted on a single base 34, with the reflector in direct line with the face of the screen and the refractors set at opposite sides of the reflector and on lines converging toward said screen.

The reflector 30 comprises a main hollow metallic casing whose back or rear portion 35 is of rectangular outline and whose front portion 36 is tubular and has at its outer end a glass disk 37 held in place by a bezel 38. The back portion 35 of the reflector casing contains a reflector 39 which is stationary and set at an angle of forty-five degrees from the vertical, being arranged to reflect images through the disk 37 and upon the ground glass disk 40 of the screen 31, one reflected image 41 being thus shown in Fig. 10.

20 In an upper extension 42 of the portion 35 of the reflector casing, is mounted a prism 43 whose lower flat horizontal face is directly over the reflector 39 and whose back inclined face is exposed to have placed thereon an article 44, as a plate, film, card or piece of wood or other substance, bearing or carrying the object or design or outline or grain, it is desired shall be reflected upon the reflector 39 and be thereby impressed on or transmitted to the screen 31. Within said portion 35 of the reflector casing is positioned an electric lamp 44, and said portion 35 has at its back end a door 45 hinged at its lower edge and adapted to be held in closed position by any suitable latches 46 (Figs. 1 and 11). The upper edge of the door 45 is flared outwardly to form a ledge or shelf 47 to support the article 44 when placed on the prism 43, as shown in Fig. 8.

40 The reflector 30 is secured upon a pedestal 48 and the screen 31 upon a corresponding pedestal 49.

The refractor mechanisms 32, 33 are alike in all their details, and in Figs. 2 to 7 inclusive I have shown in detail the refractor mechanism 32, while in Fig. 1 I illustrate in plan both of said refractor mechanisms. While describing the refractor mechanism 32 the reference numerals used will be applied 50 to the illustration of the refractor mechanism 33, since the parts are the same in both mechanisms.

The refractor mechanism 32 comprises a main tubular or barrel portion 50 having at its back end a reflector 51 and at its front end a removable tubular section 52 containing a double convex or other suitable lens 53 held in a band or ring frame 54, which by means of central transverse trunnions 55 is pivotally mounted in said tubular section 52. The lens 53 is tilttable to various angles, as required, and the degrees of these angles are indexed on the refractor mechanism, as hereinafter explained. The section 52 may be secured on the main section 50 by means

of a set screw 56 or in any suitable or convenient manner. The main section 50 contains in its rear portion an electric lamp 57, and said portion is pivotally mounted in the upper portion of a transverse yoke 58 (Fig. 6), being held therein on transverse trunnions 59 and being tilttable to various angles, as may be required, the degrees of which angles are indexed on the refractor mechanism, as hereinafter explained. The yoke 58 has a downwardly extending supporting post 60 whose lower end is reduced to form a pivot 61, which is secured in a vertical hole 62 in the base 34 by means of a washer 63 and nut 64, said washer and nut being within a socket 65 formed in said base 34 at the lower end of said hole 62. The yoke 58 is thus secured on a vertical pivot and may be swiveled laterally for the purpose of adjusting the main section 50 and its parts laterally on a vertical axis to any desired or required angle, the degree of which angle is indexed on the refractor mechanism, as hereinafter explained. The main section 50 is tilttable on a horizontal axis regardless of any lateral adjustment it may receive from the yoke 58, and is adjustable on a vertical axis from the yoke 58 regardless of any adjustment it may receive on or from the transverse trunnions 59.

The main section 50 is screw threaded, as at 66, upon its forward end portion, and has a series of horizontal guide slots 67 formed in its forward portion for the screws 68, which carry a band frame 69 within said main section 50 (Fig. 2). The frame 69 is adapted to tightly receive and carry a band frame 70 within which by means of a bezel 71 may be removably secured any one of the refractor slides 72 shown in Figs. 12 to 19 inclusive. The frame 70 preferably has a rear inwardly extending annular shoulder to form a seat for the slide 72 and a front outwardly extending annular shoulder to abut against the front edge of the band frame 69, as shown in Fig. 2. The screws 68 extend through an exterior band or ring 73, and this part 73 is fastened by horizontal screws 74 to a sectional ring 75 freely seated in an annular groove in an internally threaded band 76, which engages the thread 66 on the aforesaid main tubular section 50. When the band 76 is adjusted along the forward end of the main section 50 it carries with it, without rotating the same, the sectional ring 75, band 73, screws 68, band 69 and slide 72, this adjustment being for the purpose of positioning the slide 72 in correct relation to the lens 53 as may be required in carrying out my invention, and such adjustment being indexed on the instrument in degrees and minutes by means of a scale 77 on the forward tubular lens carrying section 52 (Fig. 1), an index finger 78 carried by the band 73 to cooperate with

said scale, a scale 79 on the rotary band 76 and an index finger 80 on the non-rotary sectional ring 75 cooperating with said scale 79.

- 5 The tilting adjustment of the lens 53 is effected manually by means of a wheel 81, a vertical worm shaft 82 on which said wheel 81 is secured and a worm wheel 83 in mesh with the worm of said shaft 82 (Fig. 3) and whose shaft 84 is a portion of the adjacent trunnion 55 of the lens carrying frame 54 (Fig. 2), and the means for indexing the angle of adjustment, in degrees and minutes, of the lens 53 comprise a disk 85 bearing on its periphery a scale 86, an index finger 87 secured to the casing section 52 in position to cooperate with said scale 86, said disk 85 being secured on the aforesaid shaft 84, a scale 109 on the face of the wheel 81 and an index finger 110 for said scale. The shaft 82 is mounted in bearings 88 secured to the casing section 52.

The means for tilting the refractor mechanism on a horizontal axis in the yoke 58, comprise a manually operative wheel 89 (Figs. 1 and 6), a vertical worm shaft 90 on whose upper end said wheel is secured, and a worm wheel 91 (Figs. 2 and 3) secured on the adjacent trunnion 59 for casing section 50 and meshing with the worm shaft 90. The rotation of the wheel 89 will obviously result in such tilting adjustment of the refractor mechanism as may be desired, and the angle of this adjustment is indexed in degrees and minutes by means of a disk 92 connected to rotate with the worm wheel 91, an index finger 93 (Fig. 6) positioned to cooperate with a scale 94 on the disk 92, a scale 95 on the face of the wheel 89 (Fig. 1) and an index finger 96 secured on the frame of the yoke 58 and cooperating with said scale 95.

The means for adjusting the refractor mechanism on a vertical axis through the post 60 and pivot 61, comprise a manually operative wheel 97 (Figs. 1 and 3), a vertical shaft 98 on whose upper end said wheel is secured, a worm 99 on the lower portion of said shaft, a worm wheel 100 (Fig. 2) in mesh with said worm, a shaft 101 on which said worm wheel is secured, a beveled pinion 102 on said shaft 101 and a beveled pinion 103 on the post 60 and in mesh with the pinion 102. When the wheel 97 is turned the motion thereof will, through the gearing described, be transmitted to the yoke 58 and the refractor carried thereby, whereby the forward end of the refractor may be adjusted toward the right or left with relation to the screen 31, as may be required, and the angle of such adjustment is indexed in degrees and minutes by a disk 104 on the shaft 101 bearing on its periphery a scale 105, a stationary index finger 106 (Fig. 3) cooperating with said scale, a scale 107 on

the face of said wheel 97 and a stationary index finger 108 cooperating with said scale 107.

The method of employing the mechanism hereinbefore described may be understood if it be considered that the object plate 44 of Fig. 8 is the plate shown in Fig. 20, that the object delineated on that plate has been reflected onto the screen 31, as shown in Fig. 10, and that the refractors 32, 33 are to be adjusted to such angles as that the refractory lines impressed by the proper slides 72 and lenses 53 onto the screen 31 shall exactly coincide with said outline 41 reflected onto the screen from the object plate 44, to the end that said angles and the adjustment of the slide or slides made use of when ascertained by the indexes hereinbefore identified, may be transmitted to another having a similar dioptragraph, so that such person may by following the data transmitted adjust his instrument to reproduce through the lenses thereon and his standard slides, the aforesaid outline 41 on his screen, from which the same may be photographed or otherwise copied. In following out this illustration, the object's irregular outline 41 having been reflected onto the screen 31, I insert in each refractor a standard transparent slide 72 of the type shown in Fig. 12 bearing an upwardly extending arc hemispherical line 109. I then adjust the slides 72 longitudinally in the refractors and adjust the refractors and their parts manually by the means hereinbefore described, until the refracted outlines produced on the screen 31 from the slides 72 and lenses 53 exactly coincide with the said outline 41, the transformation stages of the outlines 109 on the slides 72 to that shown in Fig. 10 being represented in Figs. 21, 22, 23 and 24, Fig. 21 showing primary refracted images of the two slides 72, Fig. 22 disclosing the enlargement of said images by the adjustment of the slides nearer to the lenses 53, Fig. 23 illustrating the lateral displacement of said refracted images by the lateral adjustment of the forward ends of the refractors 32, 33, in a direction from each other; Fig. 24 showing the vertical displacement of the image from one slide 72 by a vertical tilting or adjustment of its refractor on the horizontal axis of the same and Fig. 24 illustrating the final refracted image coinciding with the reflected object image found on the plate 44.

The next step is to make a note of the indexed adjustments of the parts of the instrument, or the dioptragraphic angle of the irregular line 41. If now we cut out the reflector 30 entirely and restore all the adjustments of the refractors 32, 33 to zero, the outline 41 may be reproduced on the screen 31 by simply resetting the refractors and their parts in accordance with the fore-

going noted index adjustments. Obviously anyone having a similar dioptragraph and slides may reproduce on his instrument the aforesaid irregular outline 41, upon receiving the slide number and data as to said index adjustments from the holder of the primary instrument. If the irregular outline 41 should be meant to represent a cam requiring to be made in Europe, the directions 10 for reproducing the outline on a similar instrument there could be forwarded by cable.

The invention has a wide application to many practical uses and it will not be necessary to prolong this specification by a recital of them. I particularly desire to employ the instrument for ascertaining the diographic impression of finger prints so that the data as to such impressions may be transmitted abroad and the impressions reproduced there with the use of a corresponding instrument. If the conventional finger print indicated in Fig. 25 is to be reproduced on the screen 31, I will use four of the refractor mechanisms and arrange in them 20 the four slides of the types shown in Figs. 12, 14, 17 and 19 and then make the necessary adjustments to refract the image shown in Fig. 25.

In many instances only one refractory mechanism is necessary of employment, depending on the outline to be refracted on the screen 31. In other instances two refractory mechanisms, as for the outline 41, are required, and in other instances three or 35 more of said mechanisms are required.

The invention is not limited to the mechanical detail hereinbefore described nor to the special outlines shown on the slides illustrated in Figs. 12 to 19 inclusive, since 40 these details and said outlines may be varied or modified without departure from the spirit of my invention and within the scope of the appended claims.

What I claim as my invention and desire 45 to secure by Letters Patent, is:

1. Mechanism of the character described for ascertaining data with respect to an object outline for the reproduction of that outline from such data by the same or similar 50 mechanism in the absence of said object outline, comprising a screen on which the object outline is delineated, a refractor mechanism arranged in operative relation to said screen and a transparent slide mounted in said refractor mechanism and bearing an outline to be transformed on the screen to coincide 55 with said object outline, said refractor mechanism comprising a barrel portion having a tiltable lens in its front end, reflecting means at its opposite end, a longitudinally adjustable frame carrying said slide intermediate 60 said ends, means for indexing the tiltable adjustment of said lens and means for indexing the adjustment of said slide toward and from said lens.

2. Mechanism of the character described for ascertaining data with respect to an object outline for the reproduction of that outline from such data by the same or similar mechanism in the absence of said object outline, comprising a screen on which the object outline is delineated, a refractor mechanism arranged in operative relation to said screen and a transparent slide mounted in said refractor mechanism and bearing an outline to be transformed on the screen to coincide with said object outline, said refractor mechanism comprising a barrel portion having a tiltable lens in its front end, reflecting means at its opposite end, a longitudinally adjustable frame carrying said slide intermediate 70 said ends, means for tilting said barrel portion on a horizontal axis, means for indexing the tiltable adjustment of said lens, means for indexing the adjustment of said slide toward and from said lens.

3. Mechanism of the character described for ascertaining data with respect to an object outline for the reproduction of that outline from such data by the same or similar mechanism in the absence of said object outline, comprising a screen, a reflector mechanism for reflecting the object outline directly from the object onto said screen, a refractor mechanism arranged in operative relation to said screen and a transparent slide mounted in said refractor mechanism and bearing an outline to be transformed on the 80 screen to coincide with said object outline, said refractor mechanism comprising a barrel portion having a tiltable lens in its front end, reflecting means at its opposite end, a longitudinally adjustable frame carrying 85 said slide intermediate said ends, means for indexing the tiltable adjustment of said lens and means for indexing the adjustment of said barrel portion on its horizontal axis.

4. Mechanism of the character described for ascertaining data with respect to an object outline for the reproduction of that outline from such data by the same or similar mechanism in the absence of said object outline, comprising a screen, a reflector mechanism for reflecting the object outline directly from the object onto said screen, a refractor mechanism arranged in operative relation to said screen and a transparent slide mounted in said refractor mechanism and bearing an outline to be transformed on the 90 screen to coincide with said object outline, said refractor mechanism comprising a barrel portion having a tiltable lens in its front end, reflecting means at its opposite end, a longitudinally adjustable frame carrying 95 said slide intermediate said ends, means for indexing the tiltable adjustment of said lens and means for indexing the adjustment of said slide toward and from said lens.

4. Mechanism of the character described for ascertaining data with respect to an object outline for the reproduction of that outline from such data by the same or similar mechanism in the absence of said object outline, comprising a screen, a reflector mechanism for reflecting the object outline directly from the object onto said screen, a refractor mechanism arranged in operative relation to said screen and a transparent slide mounted in said refractor mechanism and bearing an outline to be transformed on the 100 screen to coincide with said object outline, said refractor mechanism comprising a barrel portion having a tiltable lens in its front end, reflecting means at its opposite end, a longitudinally adjustable frame carrying 105 said slide intermediate said ends, means for indexing the tiltable adjustment of said lens and means for indexing the adjustment of said slide toward and from said lens.

- dexing the adjustment of said slide toward and from said lens and means for indexing the adjustment of said barrel portion on its horizontal axis.
5. Mechanism of the character described for ascertaining data with respect to an object outline for the reproduction of that outline from such data by the same or similar mechanism in the absence of said object outline, comprising a screen on which the object outline is delineated, a plurality of corresponding refractor mechanisms arranged at an angle to and pointed at said screen, and transparent slides mounted in said refractor mechanisms and bearing outlines to be combined and transformed on said screen to coincide with said object outline, each refractor mechanism comprising a barrel portion having a tiltable lens in its front end, reflecting means at its opposite end, a longitudinally adjustable frame carrying said slide intermediate said ends, means for indexing the tiltable adjustment of said lens and means for indexing the adjustment of said slide toward and from said lens.
6. Mechanism of the character described for ascertaining data with respect to an object outline for the reproduction of that outline from such data by the same or similar mechanism in the absence of said object outline, comprising a screen on which the object outline is delineated, a plurality of corresponding refractor mechanisms arranged at angles to and pointed at said screen and transparent slides mounted in said refractor mechanisms and bearing outlines to be combined and transformed onto said screen to coincide with said object outline, each refractor mechanism comprising a barrel portion having a tiltable lens in its forward end, reflecting means back of the slide, means for tilting said barrel portion on a horizontal axis, means for adjusting the forward end of the barrel portion laterally on a vertical axis, means for indexing the tiltable adjustment of said lens, means for indexing the adjustment of said barrel portion on its horizontal axis and means for indexing the lateral adjustment of said barrel portion on its vertical axis.
9. Mechanism as claimed in claim 8, comprising a reflector mechanism by which the object outline is reflected onto said screen directly from the object.
10. Mechanism as claimed in claim 6, in which each refractor mechanism comprises a frame carrying the slide, means for adjusting said frame to position the slide with relation to the screen and means for indexing the adjustment of said frame.
11. Mechanism as claimed in claim 7, in which each refractor mechanism comprises a frame carrying the slide, means for adjusting said frame to position the slide with relation to the screen and means for indexing the adjustment of said frame.
12. Mechanism as claimed in claim 8, in which each refractor mechanism comprises a frame carrying the slide, means for adjusting said frame to position the slide with relation to the screen and means for indexing the adjustment of said frame.
13. Mechanism as claimed in claim 6, comprising a reflector mechanism by which the object outline is reflected onto said screen directly from the object.
14. Mechanism as claimed in claim 7, comprising a reflector mechanism by which the object outline is reflected onto said screen directly from the object.
15. Mechanism as claimed in claim 3, in which the reflector mechanism comprises a forward barrel portion, a rear chambered portion containing an inclined reflector and back thereof, an electric lamp and a prism seated over said rear portion above said re-
- tion on a horizontal axis, means for indexing the tiltable adjustment of said lens and means for indexing the adjustment of said barrel portion on its horizontal axis.
8. Mechanism of the character described for ascertaining data with respect to an object outline for the reproduction of that outline from such data by the same or similar mechanism in the absence of said object outline, comprising a screen on which the object outline is delineated, a plurality of corresponding refractor mechanisms arranged at angles to and pointed at said screen and transparent slides mounted in said refractor mechanisms and bearing outlines to be combined and transformed onto said screen to coincide with said object outline, each refractor mechanism comprising a barrel portion having a tiltable lens in its forward end, reflecting means back of the slide, means for tilting said barrel portion on a horizontal axis, means for adjusting the forward end of the barrel portion laterally on a vertical axis, means for indexing the tiltable adjustment of said lens, means for indexing the adjustment of said barrel portion on its horizontal axis and means for indexing the lateral adjustment of said barrel portion on its vertical axis.

reflector and having an exposed rear inclined face on which the object is placed.

16. Mechanism as claimed in claim 7, in which the reflector mechanism comprises a forward barrel portion, a rear chambered portion containing an inclined reflector and back thereof, an electric lamp and a prism seated over said rear portion above said reflector and having an exposed rear inclined face on which the object is placed.

17. Mechanism as claimed in claim 8 comprising a reflector mechanism by which the object outline is reflected onto said screen directly from the object, and in which the reflector mechanism comprises a forward barrel portion, a rear chambered portion containing an inclined reflector and back thereof, an electric lamp and a prism seated over said rear portion above said reflector and having an exposed rear inclined face on which the object is placed.

18. Mechanism as claimed in claim 1, in which the lens is mounted in a ring frame having horizontal trunnions journaled in said refractor mechanism and on one of which is a pinion wheel, and in which a manually operative worm shaft is engaged with said pinion for tilting said lens, said shaft having a hand wheel on one end, and in which the means for indexing the angular adjustment of the lens comprises a graduated wheel rotatable with said pinion wheel, a scale on said hand wheel, and index fingers for cooperation with the scales on said graduated wheel and said hand wheel.

19. Mechanism as claimed in claim 3, in which the lens is mounted in a ring frame having horizontal trunnions journaled in said refractor mechanism and on one of which is a pinion wheel, and in which a manually operative worm shaft is engaged with said pinion for tilting said lens, said shaft having a hand wheel on one end, and in which the means for indexing the angular adjustment of the lens comprises a graduated wheel rotatable with said pinion wheel, a scale on said hand wheel, and index fingers for cooperation with the scales on said graduated wheel and said hand wheel.

20. Mechanism as claimed in claim 6, in which the lens is mounted in a ring frame having horizontal trunnions journaled in said refractor mechanism and on one of which is a pinion wheel, and in which a manually operative worm shaft is engaged with said pinion for tilting said lens, said shaft having a hand wheel on one end, and in which the means for indexing the angular adjustment of the lens comprises a graduated wheel rotatable with said pinion wheel, a scale on said hand wheel, and index fingers for cooperation with the scales on said graduated wheel and said hand wheel.

21. Mechanism as claimed in claim 8, in

which the lens is mounted in a ring frame 65 having horizontal trunnions journaled in said refractor mechanism and on one of which is a pinion wheel, and in which a manually operative worm shaft is engaged with said pinion for tilting said lens, said 70 shaft having a hand wheel on one end, and in which the means for indexing the angular adjustment of the lens comprises a graduated wheel rotatable with said pinion wheel, a scale on said hand wheel, and index fingers 75 for cooperation with the scales on said graduated wheel and said hand wheel.

22. Mechanism as claimed in claim 6, in which each refractor mechanism comprises a frame carrying the slide, means for adjusting said frame to position the slide with relation to the screen and means for indexing the adjustment of said frame, and in which the frame carrying the slide is non-rotary and is coupled to a rotary frame 80 having threaded engagement with the barrel portion of the refractor mechanism, and in which the means for indexing the adjustment of said slide comprises a scale on said rotary frame, a stationary finger cooperating with said scale, a scale on said barrel portion and a finger carried by said non-rotary frame cooperating with said scale on said barrel portion. 90

23. Mechanism of the character described for ascertaining data with respect to an object outline for the reproduction of that outline from such data by the same or similar mechanism in the absence of said object outline, comprising a screen on which the object outline is delineated, a refractor mechanism arranged in operative relation to said screen, and a transparent slide mounted in said refractor mechanism and bearing an outline to be transformed onto the screen to coincide with said object outline, said refractor mechanism comprising a barrel portion having a tiltable lens in its front end, means for indexing the tiltable adjustment of said lens, means for tilting said barrel portion on a horizontal axis, 100 means for adjusting said barrel portion laterally on a vertical axis, means for indexing the adjustment of said barrel portion on its horizontal axis, and means for indexing the adjustment of said barrel portion on its vertical axis, said barrel portion being mounted on trunnions in the sides of a yoke whose lower portion constitutes a pivot, the means for tilting and indexing the tiltable adjustment of said barrel portion on its horizontal axis, comprising a gear wheel on one of said trunnions, a manually operative worm shaft engaged with said gear wheel and having on one end a hand wheel bearing 105 a graduated scale, a stationary finger for cooperation with said scale, an index wheel 110 rotatable with said gear wheel and having

115

120

125

on its periphery a graduated scale and a stationary finger cooperating with said last-mentioned scale.

24. Mechanism of the character described for ascertaining data with respect to an object outline for the reproduction of that outline from such data by the same or similar mechanism in the absence of said object outline, comprising a screen on which the object outline is delineated, a refractor mechanism arranged in operative relation to said screen, and a transparent slide mounted in said refractor mechanism and bearing an outline to be transformed onto the screen to coincide with said object outline, said refractor mechanism comprising a barrel portion having a tiltable lens in its front end, means for indexing the tiltable adjustment of said lens, means for tilting said barrel portion on a horizontal axis, means for adjusting said barrel portion laterally on a vertical axis, means for indexing the adjustment of said barrel portion on its horizontal axis, and means for indexing the adjustment of said barrel portion on its vertical axis, said barrel portion being mounted on trunnions in the sides of a yoke whose lower portion constitutes a pivot, the means for adjusting said barrel portion laterally on its vertical axis and indexing said adjustment, comprising a worm shaft having on its upper end a hand wheel bearing a graduated scale, a shaft geared to said pivot and having on one end a worm wheel in mesh with the worm of said worm shaft,

a disk bearing on its periphery a scale and rotatable with said worm wheel, a stationary finger for cooperation with the scale on said hand wheel, and a stationary finger for cooperation with the scale on said disk. 40

25. The method of reproducing an original outline impressed on a screen which consists in selecting an outline differing from said original outline and transforming and impressing the same onto said original outline to coincide therewith by reflection and refraction and angular adjustments of said selected outline, indexing said adjustments, and reproducing a copy of said original outline on a screen with the use of said selected outline set with relation to a screen in accordance with said ascertained angular adjustments. 45

26. The method of reproducing an original outline impressed on a screen which consists in selecting a plurality of outlines differing from said original outline and transforming and impressing the same onto said original outline to coincide therewith by reflection and refraction and angular adjustments of said selected outlines indexing said adjustments, and reproducing a copy of said original outline on a screen with the use of said selected outlines set with relation to a screen in accordance with said ascertained angular adjustments. 50

Signed at New York city, in the county of New York and State of New York, this 13th day of November, A. D. 1924.

SEYED KHALIL.
